UNITED STATES PATENT OFFICE.

WILLIAM S. WILLIAMS, OF EAST HARTFORD, CONNECTICUT, ASSIGNOR
TO THE WILLIAMS BROTHERS MANUFACTURING COMPANY, OF CON-
NECTICUT.

GRINDER FOR FINGER-BARS AND SICKLE-BARS FOR MOWING AND REAPING MACHINES.

SPECIFICATION forming part of Letters Patent No. 434,124, dated August 12, 1890.

Application filed July 31, 1888. Renewed February 24, 1890. Serial No. 341,400. (No model.)

To all whom it may concern:

Be it known that I, WILLIAM S. WILLIAMS, of East Hartford, in the county of Hartford and State of Connecticut, have invented certain Improvements in Grinders for Finger-Bars and Sickle-Bars for Mowing and Reaping Machines, of which the following is a specification.

The cutting mechanism of mowing and reaping machines consists of a stationary bar provided with guard-fingers having fixed blades known as "ledger-plates" therein, and of a reciprocating sickle-bar having triangular knives, which pass through the guard-fingers over the ledger-plates.

The aim of my invention is to provide a machine by which the ledger-plates may be rapidly ground and sharpened at their edges while in place on the finger-bar, and to adapt the same machine for the grinding of the knives of the sickle-bar.

My machine comprises a frame with a rotary grinding stone or wheel, peculiar adjustable supports for the parts to be ground, and a mechanism for automatically moving the rests to and from the wheel when the machine is in action.

In the accompanying drawings, Figure 1 is a side elevation of my machine. Fig. 2 is a top plan view of the same. Fig. 3 is a section on the line $x-x$ of Figs. 1 and 2. Fig. 4 is a front elevation of the rest or support for the finger-bar. Fig. 5 is a top plan view of the same. Fig. 6 is a top plan view of the rest employed in grinding sickle-knives. Fig. 7 is a side elevation of the same. Fig. 8 is an edge view of the same.

In constructing my machine I form or secure upon a suitable base A a standard B, having at its upper end bearings to sustain a horizontal shaft C, which is provided at one end with a hand-crank D, and near the other end with a beveled gear-wheel E. This gear I engage with a smaller gear F, secured on a second horizontal shaft G, carrying a grinding-wheel H of emery or other suitable material. The grinder-shaft G is sustained in the standard B and in a second standard A',

rising from the base, whereby the grinding-wheel is accurately guided in its rotation 50 while receiving a rapid motion through the intermediate gear from the crank. Upon the base opposite the edge of the grinding-wheel I locate a plate I, slotted, and secured by a bolt J passing through the slot, so that it may 55 be moved to and from the wheel.

K represents an upright round post mounted between ears i on the plate I, and connected thereto by a horizontal supporting-pivot i', so that its upper end may swing to and from 60 the wheel. The lower end of the post has a rigid arm k carried toward the stone and bent at its end at a right angle to form a crank or wrist k', which is connected by a pitman k² to a crank-pin k³ on the end of the shaft 65 C, whereby the post K is given a constant vibration to and from the stone.

On the upper end of the vibrating post I mount a sleeved plate L, which may be revolved or adjusted vertically thereon at will. 70 It is sustained by a pin k⁴ seated in one of a series of holes in the post and changeable from one to another at will. This pin, by encountering the walls k⁵ of a notch in the lower end of a sleeve, limits the rotary motion 75 of the sleeve. A set-screw k⁶ mounted in the sleeve and acting against the post holds the sleeve rigidly in any position in which it may be placed.

M indicates a rest or support for the finger-bar located between the post and the stone and connected by an approximately horizontal pivot m to the sleeve L, so that it may be given an inclination from the horizontal to the right or left, according as it is required to 80 grind the ledger-plates on one edge or the other. Arms m' extend rearward from the rest or support with threaded necks passed through a bar m² and provided with nuts m³, whereby the rest M may be placed at any required inclination to the post and the horizon. 85 The rest is formed with forwardly and upwardly extending arms m⁴, having thereon a board or plate m⁵ to receive the finger-bar and sustain the same in proper position for 90 presentation to the edge of the stone. Set- 95

screws m^6 passed upward through the arms of the rest serve as a means of raising the forward edge of the finger-bar and determine the angle of its presentation to the stone. 5 Set-screws m^7 passed through the rear side of the rest act against the rear edge of the finger-bar to hold the same forward on the rest that the stone may be certain to act to the proper depth between the guard-fingers.

10 In order that the automatic advance of the rest and finger-bar toward the grinding-wheel may be stopped at one point or another—that is to say, at a greater or less distance from the edge of the wheel as the width or other peculiarity of the bar may render necessary—I give the wrist k' an inclination from the horizontal, as shown in Fig. 3, and connect the pitman to a sleeve G, which is arranged to slide on the wrist and secured by a set-screw 15 g . By moving this sleeve along the wrist, and securing it in different positions, the post may be caused to stop in its forward movement at any required distance from the grinding-wheel. As a further means of limiting the 20 advance of the post and rest, and as a means of limiting the length of the vibration, I make the throw of the crank variable in any suitable manner, preferably by providing the disk on the end of the shaft C, at different distances from the axis, with a series of holes, 25 as shown in Fig. 3, into either of which the crank-pin may be secured at will.

30 It will be observed that the arms of the rest to sustain the finger-bar are rigid, so that the bar is given a positive support, and sustained at the required angle in its cross-section to the stone. In the grinding of sickle-knives, this rigid support is not desirable. On the contrary, it is desirable to have the knives 35 rest freely and with their entire weight upon the upper face of the stone. I therefore provide a second rest S, which may be applied to the sleeve L in place of the rest M. This second rest consists, first, of a plate s adapted to fit upon the pivot m , and provided with a curved slot to receive a clamping-screw s' , so that it may be inclined to the right or left. To this plate is hinged the rest-plate s^2 , so that it may be tipped upward and downward at 40 the edge nearest the grinding-stone. On this plate s^2 is placed a clamp s^3 , guided and held in place by bolts s^4 and sustained when released by lifting-springs s^5 . An eccentric lever s^6 , mounted on a stud s^7 , and acting beneath an overlying stationary bar s^8 , serves to force the parts together, and thus confine the cutter-bar, which is inserted between the clamp s^3 and plate s^2 .

45 When the above device is placed on the sleeve, the clamp serves to hold the cutter-bar and present it in proper relation to the grinding-wheel, allowing it, as it is moved to and from the grinding-wheel, to rest thereon and to sink as it is ground away.

50 In using the machine for the grinding of finger-bars, the bar is laid upon the rest M and sustained thereby in position. The rest

is then adjusted to the required inclination to the right or left, the vibration of the post suitably regulated, and the driven crank turned 70 to set the wheel in motion. The post being automatically vibrated, advances the post toward the wheel and automatically withdraws it, so that the edge of the wheel is caused to advance along and sharpen the edge of the 75 first ledger-plate. The bar is then moved endwise on the rest, the next plate sharpened in like manner, and so on repeatedly until all the plates are sharpened on one edge, after which the rest is tipped in the opposite direction, the movement of the lever reversed, and the plates ground one after another on their opposite edges.

In grinding the finger-bars I prefer to employ a wheel with a beveled edge, as represented in Figs. 1 and 2; but a thin grinding-wheel with flat faces may be employed.

In the grinding of cutter or sickle bars I prefer to use a stone with a square or rectangular edge.

Having thus described my invention, what I claim is—

1. The grinding-wheel and the driving-shaft C geared thereto, in combination with the vibratory post K, its crank-arm, the pitman, 95 and the crank on the driving-shaft, the sleeve adjustable around the post, and the rest pivoted to and adjustable as to its lateral inclination upon the sleeve.

2. In a machine for sharpening harvester-knives, the grinding-wheel, the shaft C geared directly thereto and provided with the crank k^3 , in combination with the pivoted vibratory post provided with the rest to sustain the cutter, the arm extending rigidly from the lower 100 end of the post and provided with the laterally-inclined wrist, as described, the pitman attached at one end to the crank, the slide pivoted to the lower end of the pitman and adjustable lengthwise upon the inclined wrist, 105 whereby the rest may be advanced toward the stone a greater or less distance, as circumstances may require.

3. The grinding-wheel and the driving-shaft geared to said wheel and provided with crank 115 k^3 , in combination with the vibratory post K, having the angular rigid arm k , the pitman connecting said arm with the crank k^3 , the rest for the cutter connected with the post through a horizontal pivot, in order that its lateral inclination may be reversed, and the post-sustaining plate L, adjusted, as described, to and from the grinding-wheels.

4. In a grinding device for harvester-cutters, the grinding-wheel, in combination with the vibratory post, the rotary sleeve L thereon, the adjustable stop-pin k^4 and set-screw k^6 to receive said sleeve, the rest N, pivotally connected to the sleeve, and a clamping device uniting the rest and sleeve to maintain 120 the adjustment of the former, substantially as described.

5. In a machine for sharpening harvester-knives, the combination of the grinding-wheel,

the vibratory post K, the rest M, mounted thereon, and the upright screws m^6 , rising through the rest, whereby the inclination of the cutter with reference to the rest and the

5 stone may be varied.

6. In combination with the grinding-stone, the vibratory post, the rest mounted on said post, the upright screws m^6 , passing through the rest adjacent to the stone, and the ap-

10 proximately horizontal screws m^7 , passing

through the back of the rest to act on the rear edge of the cutter.

In testimony whereof I hereunto set my hand, this 15th day of February, 1888, in the presence of two attesting witnesses.

WILLIAM S. WILLIAMS.
